UNITED STATES PATENT OFFICE.

JOHN KERCH, OF AKRON, OHIO, ASSIGNOR TO THE XXTH CENTURY HEATING AND VENTILATING COMPANY, OF AKRON, OHIO, A CORPORATION OF OHIO.

FURNACE CONSTRUCTION.

Application filed April 9, 1923. Serial No. 630,693.

To all whom it may concern:

Be it known that I, JOHN KERCH, a citizen of the United States, and a resident of Akron, county of Summit, State of Ohio, 5 have invented certain new and useful Improvements in Furnace Construction, of which the following is a specification.

This invention relates to furnaces and particularly to furnaces of the hot air type 10 such as used, for example, for domestic heating purposes. The invention also relates more specifically to that type of furnace which is composed or built up of several sections or castings and the object of the invention is to improve upon the sealing means 15 between the several sections.

Heretofore, the furnaces of this type have been provided at the junction between the several parts with sealing means which 20 has not been entirely satisfactory and it is the object of the invention to so construct and arrange the furnace sections that improved sealing means may be provided.

In prior constructions of this type a simple ledge has been provided along the upper 25 edge of each section with an outwardly upwardly extending flange and the lower edge of the next section above has been seated therein, the ledge being provided with a suitable cement or filler to close the joints 30 about the furnace. In use the sealing means has proven inadequate to prevent gases from oftentimes leaking out through the cracks of the furnace and mingling with the heated 35 air. At times explosions will occur in furnaces and unless the force of the explosion can be expended through the door openings, they will often blow out through the joints in the furnace, the sealing means which has 40 been described offering insufficient resistance to the force of the explosion.

With the improved construction herein shown, these faults are remedied and while the description and showing is detailed, the 45 invention is not necessarily limited to these details as will be understood from the scope of the attached claims, which are intended to cover the invention as broadly as permitted by the prior art.

50 In the drawings:

Figure 1 is a perspective view of a furnace of the general type described, parts being broken away to illustrate the joints; and

55 Figure 2 is a vertical section through one side of the furnace.

While the invention is shown as applied to a certain type of furnace, it will be understood that it is not limited to this use alone and while a type of furnace suitable for soft coal is shown, the invention is applicable to hard coal furnaces as well.

The furnace comprises the ring support or frame work at the base indicated by the numeral 1, which is adapted to support the furnace and the outer casing enclosing the 60 air space as will be understood. Supported upon the base and in the order named are the ash pit section 2, the fire pot section 3, the feed section 4, and the dome or radiator 5.

The base is provided with a ledge 6 and with a surrounding flange 7 and the lower edge of the ash pit seats on the ledge and is formed with a horizontal flange or rib 8 which overlies the top of the flange. The 70 upper edge of the ash pit is provided with a similar ledge 9 and flange 10 and the lower edge of the fire pot rests on the ledge 9 and is provided with a flange or rib 11 which overlies the flange 10.

The upper edge of the fire pot is formed with a circumferential groove 12 on either side of which are continuous vertical flanges 13. The lower edge of the feed section is provided with a circular rib 14 which seats 80 in the groove and in addition is enlarged at its lower edge to provide flanges or ribs 15 on both sides thereof which overlie the flanges 13. The groove 12 with its flanges 13 and the rib 14 with the flanges 15 provide a 90 three-point or three-line contact at the crack between the fire pot and the feed section. As this is the most important joint of the furnace and the one at which there is the greatest liability for leakage, the especially secure joint afforded by the three-line contact is located here.

The feed section is formed with the conical or tapered surface 16 which terminates in the vertically ribbed or undulatory surface 100 17 and around the upper edge of the feed section is provided the continuous groove 18 formed between the vertical flanges or ribs 19. The radiator is formed with vertical undulations 20 to correspond to the 105 surface 17 and the lower edge of the radiator is provided with the rib 21 which seats within the groove 18, and also with a laterally extending flange 22 which overlies one of the flanges 19. While the joint shown 110

at the junction between the radiator and the feed section is not as secure as that shown just below, it is sufficiently secure to serve the purpose at this joint, at which the liability for leakage is not so great.

In assembling or building the furnace, the various joints are sealed with the usual cement, which in the upper edges of the fire pot and feed section is held within the 10 grooves 12 and 18. When the next section is put in place the mating ribs are tightly sealed and the joint is further reinforced by the outstanding flanges 15 and 22 lying over their respective ribs 13 and 19. The cement 15 filling the grooves and on the top of the ribs effectually seals the joints as has been described, the three-point contact at the top of the fire pot being especially efficacious.

What I claim is:

20 1. In a furnace construction comprising a fire pot and a feed section placed thereon, the fire pot having a continuous groove about its upper edge, a continuous rib about the lower edge of the feed section, the 25 groove being bounded by continuous flanges and laterally extending flanges on the sides of the feed section overlying the first named flanges whereby a continuous three line contact is provided about the joint between the 30 feed section and the fire pot.

2. In a furnace construction composed of a series of sections placed one above the other, one of said sections having a continuous groove about its upper edge, a continuous rib on the lower edge of the section thereabove, said rib being receivable within the groove and laterally extending flanges on the upper of said sections overlying the 35 walls about the said groove on both sides thereof whereby a continuous three line contact is provided about the joint between the 40 sections.

3. In a furnace construction composed of a series of sections placed one above the 45 other, one of said sections being a fire pot, a feed section above the fire pot, said feed section being formed with vertical undulations therein, a radiator above the feed section formed with corresponding vertical undulations, a continuous groove bounded by vertical walls on the upper edge of the fire pot and a similar groove on the upper edge 50 of the feed section, the feed section and radiator seating at their lower edges within respective grooves and lateral flanges on the section overlying a wall of each said groove.

4. In a furnace construction composed of a series of sections placed one above the 60 other, one of said sections being a fire pot,

a feed section above the fire pot, and a radiator above the feed section, a continuous groove bounded by vertical walls on the upper edge of the fire pot and a similar groove on the upper edge of the feed section, the feed section and radiator seating at their lower edges within respective grooves and a lateral flange on the feed section and radiator overlying a wall of each 65 said groove.

5. In a furnace construction, a fire pot section and a feed section on said fire pot, spaced continuous vertical walls about the upper edge of the fire pot providing a circumferential groove, a rib on the lower edge 70 of the fire pot seated within the groove and laterally extending flanges adjacent the lower edge of the fire pot overlying the walls.

6. In a furnace construction, a plurality 80 of sections one above the other, spaced continuous vertical walls about the upper edge of a lower section providing a circumferential groove, the lower edge of an upper section seating within the groove and laterally extending flanges on both sides of the upper section overlying the vertical walls whereby a continuous three line contact is afforded about the fissure between the sections.

7. In a furnace construction, a plurality 85 of sections one above the other, spaced continuous vertical walls about the upper edge of a lower section providing a circumferential groove, the lower edge of an upper section seating within the groove and a laterally extending flange on the upper section 90 overlying a vertical wall.

8. In a furnace construction, a plurality 100 of sections one above the other, spaced vertical walls about an edge of one section providing a continuous groove therebetween, the mating edge of the adjacent section received within the groove and laterally extending flanges on both side of the last 105 named section opposite said walls and providing a continuous three line contact about the fissure between the sections.

9. In a furnace construction, a fire pot section, the upper edge being formed with 110 two parallel spaced walls to provide a continuous circumferential groove therebetween, and a second furnace section above the fire pot section having its lower edge seated within the groove and laterally extending flanges on the second section overlying the walls whereby a continuous three line contact is afforded above the fire pot section.

JOHN KERCH.
